UNITED STATES PATENT OFFICE.

FABIUS S. ELMORE, OF WASHIINGTON, DISTRICT OF COLUMBIA, ASSIGNOR TO
MARVIN C. STONE, OF SAME PLACE.

DESIGN FOR A FAN.

SPECIFICATION forming part of Design No. 24,903, dated November 19, 1895.

Application filed September 28, 1895. Serial No. 564,043. Term of patent 14 years.

To all whom it may concern:

Be it known that I, FABIUS S. ELMORE, a citizen of the United States, residing at Washington, in the District of Columbia, have invented and produced a new and original Design for Fans, of which the following is a specification, reference being had to the accompanying drawing, which represents my improved design.

10 The leading feature of my design consists of the conventionalized representation or imitation of an open razor, the blade and the handle constituting, respectively, the inclined edges of the fan, as plainly shown in the drawing.

15 A represents the razor-blade, and B its handle, connected as usual by the pivot C, the parts being shown in an open position and joined by the fan proper D, containing a series 20 of radiating lines E, representing the folds of the fan.

The design thus produced has the appearance of the well-known segmental fan-leaf connected to and between the parts of an open razor, the blade constituting one of the inclined edges of the leaf and the handle the other, the bowed back of the blade and the bowed back of the handle as conventionally produced by me forming the outer edges, respectively, of the fan-handle.

25 Having thus described my invention, what I claim is—

30 The design for a fan substantially as herein shown and described.

In testimony whereof I hereunto set my hand this 25th day of September, 1895, in the presence of two attesting witnesses.

FABIUS S. ELMORE.
